[57] CLAIM

The ornamental design for wheeled trash container, as shown and described.

DESCRIPTION

FIG. 1 is a perspective view of a wheeled trash container showing our new design, the view being taken generally from the front and side;

FIG. 2 is a perspective view of a wheeled trash container showing our new design, the view being taken generally from the back and side;

FIG. 3 is a front elevational view of the wheeled trash container of FIG. 1;

FIG. 4 is a back elevational view of the wheeled trash container of FIG. 1;

FIG. 5 is a right end elevational view of the wheeled trash container of FIG. 1, the left end elevational view being a mirror image thereof; and,

FIG. 6 is a top plan view of the wheeled trash container of FIG. 1.
